COMBINED PHONOGRAPH AND RADIO OR SIMILAR ARTICLE

Carl Yurdin, Port Washington, N.Y., assignor to Harman-Kardon, Inc., Philadelphia, Pa., a corporation of Delaware

Filed Mar. 4, 1966, Ser. No. 1,298

Term of patent 14 years

(Cl. D56—4)

Fig. 1

Fig. 2

Fig. 3

Fig. 4

FIGURE 1 is a front, top and right side perspective view of a combined phonograph and radio or similar article, showing my new design;

FIGURE 2 is a rear elevation view thereof;

FIGURE 3 is a left side view thereof; and

FIGURE 4 is a top view thereof.

The bottom is essentially plain and unornamented.

The dominant features of my new design are shown in solid lines in the drawing.

I claim:

The ornamental design for a combined phonograph and radio or similar article, as shown and described.
